UNITED STATES PATENT OFFICE

93,037

DESIGN FOR A BRACELET

Charles B. Oulton, Attleboro, Mass., assignor to
Plastic-Craft Novelty Company, Inc., a corpora-
tion of Rhode Island

Application December 14, 1933, Serial No. 50,082

Term of patent 3½ years

To all whom it may concern:

Be it known that I, CHARLES B. OULTON, a citizen of the United States of America, residing at Attleboro, in the county of Bristol and State of Massachusetts, have invented a new, original, and ornamental Design for Bracelets, of which the following is a specification, reference being had to the accompanying drawing, forming part thereof.

Figure 1 is a side elevational view of the bracelet, showing my new design;

Figure 2 is a plan view of an extended strand to form the bracelet; and

Figure 3 is a vertical cross-sectional view taken on line 3—3 of Figure 1.

The salient design characteristic is shown more clearly in Figure 3 and embodies the inner and outer concentric arcuate sections of the band or bracelet, with the inner and outer sides thereof being curved outwardly.

I claim:—

The ornamental design for a bracelet, as shown and described.

CHARLES B. OULTON.
